METAL SCROLL WORK FOR USE IN BUILDINGS

Harry A. Bell, Oklahoma City, Okla.

Application July 26, 1954, Serial No. 31,586

Term of patent 7 years

(Cl. D54—2)

FIG. 1

FIG. 2

FIG. 3

To all whom it may concern:

Be it known that I, Harry A. Bell, a citizen of the United States and resident of Oklahoma City, Oklahoma, have invented a new, original, and ornamental Design for Metal Scroll Work for Use in Buildings, of which the following is a specification, reference being had to the accompanying drawings, forming a part thereof.

Figure 1 is a side elevation of a metal scroll work for use in buildings embodying my new design.

Figure 2 is a perspective view viewed from one side and one end and the top of the same, and

Figure 3 is a similar view, the scroll being inverted with respect to Figure 2, and as viewed from the opposite

side of the scroll and the opposite end with respect to Figure 2.

I claim:

The ornamental design for metal scroll work for use in buildings, as shown.
